UNITED STATES PATENT OFFICE

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK

SHIMMED RAIL JOINT

Application filed September 10, 1930. Serial No. 481,022.

This invention relates to rail joints, and has particular reference to improvements in rail joints of the type in which the joint bar is supported at its ends upon the rail bases and has head clearance at its ends from the rail heads, and which medially affords support from the rail heads at the ends thereof.

According to prior practice, the joint bars of rail joints of the foregoing type have been formed for direct contact with the rails. Due, therefore, to the necessarily irregular height and section of the prior bars, the same cannot conveniently or economically be rolled, but must either be forged or cast. Accordingly, an important object of the present invention is to provide a rail joint structure of the type mentioned in which the joint bar is, or may be, of uniform height and section throughout its length to permit the same to be economically rolled.

Also, according to the prior practice of forming the joint bars of irregular height and section for direct contact with the rails, any given prior bar is adapted to fit and to be used only with rails having a single definite fishing height; and, moreover, no provision is made to permit efficient use of a prior bar in instances where wear has occurred on the undersides of the rail heads at the ends thereof. Accordingly, another important object of the present invention is to provide a rail joint structure of the type mentioned in which the joint bar is adapted for use with rails having different fishing heights, and in which provision is made to afford efficient support not only for the ends of new rail, but also for the ends of used rails in instances where wear has occurred on the undersides of the rail heads at their ends.

Another object of the present invention is to provide a rail joint of the character mentioned in which the joint bar possesses long life and in which the parts of the joint which are subjected to material wear may be replaced at relatively slight expense, thereby to render the joint especially desirable from an economical maintenance standpoint.

With the foregoing and other objects in view, which will become more fully apparent as the nature of the invention is better

understood, the same consists in the novel features of construction, combination and arrangement of parts as will be hereinafter more fully described, illustrated in the accompanying drawings and defined in the appended claims.

In the drawings, wherein like characters of reference denote corresponding parts in the different views:

Figure 1 is a side elevation of a rail joint constructed in accordance with one embodiment of the present invention.

Figure 2 is a transverse section on the line 2—2 of Fig. 1.

Figure 3 is a transverse section on the line 3—3 of Fig. 1.

Figure 4 is a side elevation of a rail joint constructed in accordance with another embodiment of the invention.

Figure 5 is a top plan view of the joint bar shown in Fig. 4.

Figure 6 is a transverse section on the line 6—6 of Fig. 4.

Figure 7 is a transverse section on the line 7—7 of Fig. 4.

Figure 8 is a side elevation of a rail joint constructed in accordance with another embodiment of the invention.

Figure 9 is a perspective view of the medial shim shown in Fig. 8; and

Figure 10 is a view similar to Figs. 1, 4 and 8 of an alternative embodiment of the invention.

In the illustration of each different form of the invention, the rails are designated as R, R, respectively, and the joint bar as B, the rails having the usual head fishing surfaces 10 on the undersides of their heads 11 and base fishing surfaces 12 on the upper sides of their base flanges 13, and the joint bar having head and base fishing surfaces 14 and 15, respectively, also as is usual.

According to the embodiment of the invention illustrated in Figs. 1 to 3 of the drawings, the joint bar B, which may be of any suitable cross-sectional shape, and which is, or may be, of uniform height and section throughout its length, so as to be capable of being rolled economically and with facility, is rolled or otherwise formed to have a fish-

ing height suitably less than the fishing height of the rails to which it is to be applied. Said bar is straight both horizontally and vertically, and at its ends, between the lower or base fishing surface 15 thereof and the lower or base fishing surfaces 12 of the rails R, R', are interposed shims 16, 16, respectively, whereby the bar is supported at its ends upon the base flanges of the rails with its upper or head fishing surface 14 spaced from the head fishing surfaces 10 of the rails. In addition, a shim 17 is interposed between the medial portion of the head fishing surface 14 of the bar and the head fishing surfaces of the rails at the ends of the latter, this shim being of a sufficient length to extend outward a suitable distance from the end of each rail to afford a firm support for the rail ends, but at the same time being of a length suitably less than the length of the joint bar so that the latter has head clearance at its ends from the undersides of the rail heads. Furthermore, a shim 18, which may be formed separately from the shim 17, or integral therewith, as shown in Fig. 2 of the drawings, is interposed between the base fishing surface 15 of the bar, medially thereof, and the base fishing surfaces 12 of the rails, this shim, like the shim 17, being of a sufficient length to extend outward a suitable distance from the end of each rail, but of a length suitably less than the length of the joint bar so that clearance spaces exist between the ends of said shim and the inner ends of the shims 16, 16, respectively.

Thus, in view of the foregoing, it is manifest that the present rail joint not only possesses all of the advantages of the prior rail joint heretofore mentioned, wherein the joint bar is formed to have head clearance at its ends from the undersides of the rail heads and direct contact medially with the heads of the rails and at its ends with the rail flanges, but that the present rail joint is particularly simple and economical to produce, and to maintain, inasmuch as the joint bar B may readily be rolled, and inasmuch as practically all wear takes place on the shims, which may be replaced whenever necessary at relatively low cost. Moreover, by reason of the present construction, shims of different thickness may be employed either to adapt a single joint bar B for use with rails having different fishing heights, or to compensate for any wear which may take place on the fishing surfaces of the rails or on the joint bar.

Referring now to the embodiment of the invention illustrated in Figs. 4 to 7 of the drawings, it will be observed that the construction is substantially the same as that illustrated in Figs. 1 to 3, except that the joint bar B has its ends bowed normally outward as indicated at b, b, in Fig. 5, whereby ample clearance is afforded at all times between the inner face of the joint bar at its ends and the

webs of the rails to permit the ends of the joint bar to be drawn inwardly after the medial shims 17^a and 18^a have been seated and the joint has been tightened thereby to store energy in the bar to maintain the joint tight. 70 Due to the angularity of the base fishing surfaces of the rails and the joint bar, and to bowing the ends of the joint bar outwardly while maintaining the top and bottom surfaces of the bar in the same horizontal planes, 75 respectively, which is desirable from a standpoint of simplicity and economy in production, the distance between the base fishing surfaces of the rails and the joint bar is greater at the ends of the bar than at the middle thereof. Accordingly, in instances where the ends of the joint bar are bowed outward, the shims 16^a, 16^a interposed between the ends of the joint bar and the base flanges of the rails are formed thicker than the shim 18^a, as best 80 shown in Fig. 6, to afford a bearing for the ends of the joint bar farther down or out on the rail base flanges than in the embodiment of the invention illustrated in Figs. 1 to 3, 85 wherein the joint bar is straight and the distance between the base fishing surfaces of the rails and the joint bar is uniform throughout the length of the bar. 90

In the embodiment of the invention illustrated in Figs. 8 and 9 of the drawings, the joint bar B may either be straight, as in the embodiment of the invention first shown and described, or bowed as in the embodiment of the invention illustrated in Figs. 4 to 7, the essential difference in this embodiment of the 100 invention, as distinguished from the embodiments of the invention illustrated in Figs. 1 to 7, residing in dividing the base shim 18^b either by slotting said shim as best illustrated at 19 in Fig. 9, or by forming said shim in 105 two separate sections, to provide a clearance space at the middle of the joint between the base fishing surface of the joint bar and the rail flanges for the purpose of allowing the wave motion of the rails to pass through the 110 joint and to effect loading of the rail bases at points spaced from the ends of the rails where the rail bases are better adapted to support loads than at their extreme ends. 115

The invention also contemplates the use of the shims in a manner to provide rail flange clearance from the bar at the center of the joint to ease the passing of the rail wave motion through the joint. That may be accomplished as shown in Fig. 10 by omitting the 120 central base flange shim 18, 18^a or 18^b as the case may be, and using the center of the joint only on upper shim member 17^c, combined with the end shims 16^c.

Without further description it is thought 125 that the features and advantages of the invention will be readily apparent to those skilled in the art, and it will of course be understood that changes in the form, proportion and minor details of construction may be 130

resorted to, without departing from the spirit of the invention and scope of the appended claims.

I claim:

5. 1. In a rail joint, the rails, a joint bar of less fishing height than the fishing height of the rails, shims interposed between the ends of the joint bar and the base flanges of the rails, and a shim of less length than the joint bar interposed between the medial portion of the head of the bar and the undersides of the rail heads at the ends thereof.

2. In a rail joint, the rails, a joint bar of uniform height throughout its length, and means whereby said bar is supported at its ends upon the rail flanges and whereby the bar medially supports the rail heads at the ends of the latter, said bar having head clearance at its ends from the undersides of the rail heads.

3. In a rail joint, the rails, a joint bar of less fishing height than the fishing height of the rails, shims interposed between the ends of the joint bar and the base flanges of the rails, a shim of less length than the joint bar interposed between the medial portion of the head of the bar and the undersides of the rail heads at the ends thereof, and a shim interposed between the medial base portion of the bar and the rail flanges.

4. In a rail joint, the rails, a joint bar of uniform height throughout its length having its ends deflected outwardly, and means whereby said bar is supported at its ends upon the rail flanges and whereby the bar medially supports the rail heads at the ends of the latter, said bar having head clearance at its ends from the undersides of the rail heads.

5. In a rail joint, the rails, a joint bar of less fishing height than the fishing height of the rails having head clearance at its ends from the undersides of the rail heads, and a shim interposed between the medial portion of the head of said joint bar and the undersides of the rail heads at the ends of the latter.

6. In a rail joint, the rails, a joint bar having head clearance at its ends from the undersides of the rail heads and being in load supporting relation medially with the ends of the rail heads, and shims interposed between the ends of the joint bar and the rail flanges.

7. In a rail joint, the rails, a joint bar having head clearance at its ends from the undersides of the rail heads, and being in load supporting relation medially with the ends of the rail heads, and means whereby said bar is supported upon the rail flanges at points spaced from the ends of the rails to provide a clearance space between the bar and the rail flanges at the ends of the rails.

8. In a rail joint, the rails, a joint bar supported outwardly of its medial portion upon the rail flanges and having clearance medially from the rail flanges, said bar having

head clearance at its ends from the rail heads, and a shim interposed between the medial portion of said bar and the rail heads.

9. In a rail joint, the rails, a joint bar having its ends bowed normally outward and supported upon the rail flanges, said bar having head clearance at its ends from the undersides of the rail heads, and a shim interposed between the medial portion of the head of said bar and the undersides of the rail heads at the ends of the latter.

10. In a rail joint, the rails, a joint bar of uniform height and section throughout its length and of less fishing height than the fishing height of the rails supported at its ends upon the rail flanges and having head clearance at its ends from the undersides of the rail heads, and means whereby the rail heads are supported at their ends upon the medial portion of the head of the bar.

11. In a rail joint, the rails, a joint bar of uniform height and section throughout its length and of less fishing height than the fishing height of the rails having its ends bowed normally outward and supported upon the rail flanges, said bar having head clearance at its ends from the undersides of the rail heads, and means whereby the rail heads are supported at their ends upon the medial portion of the head of the bar.

12. In a rail joint, the rails, a joint bar supported outwardly of its medial portion upon the rail flanges and having head clearance at its ends from the rail heads, and a center shim interposed between the medial portion of the bar and the rail heads.

13. In a rail joint, the rails, a joint bar of less fishing height throughout than the fishing height of the rails, said joint bar being supported outwardly of its medial portion upon the rail flanges and having head clearance at its ends from the rail heads, and a centrally located shim interposed between the medial portion of the bar and the rail heads.

In testimony whereof I hereunto affix my signature.

CLARKSON A. DISBROW.
